PLAYING PIECE FOR A GAME

Harry Zelenko, 150 E. 61st St., New York, N.Y. 10021

Filed Sept. 17, 1968, Ser. No. 13,563

Term of patent 14 years

Int. Cl. D21—01

U.S. Cl. D34—2

FIG. 1 is a left side elevational view of a playing piece for a game, showing my new design, with the top member shown in position within the toy;

FIG. 2 is a right side elevational view thereof;

FIG. 3 is a front elevational view thereof;

FIG. 4 is a rear elevational view thereof;

FIG. 5 is a top plan view thereof with the top member removed;

FIG. 6 is a bottom plan view thereof with the top member removed; and

FIG. 7 is a bottom plan view of the top member.

I claim:

The ornamental design for a playing piece for a game, substantially as shown and described.
